UNITED STATES PATENT OFFICE.

MILTON E. WINANS, OF NEWARK, NEW JERSEY, ASSIGNEE TO WESTERN ELECTRIC COMPANY, OF NEW YORK, N. Y., A CORPORATION OF ILLINOIS.

SAFETY DEVICE FOR POWER-PRESSES.

1,092,467.

Specification of Letters Patent.

Patented Apr. 7, 1914.

Application filed November 30, 1910. Serial No. 594,919.

To all whom it may concern:

Be it known that I, MILTON E. WINANS, citizen of the United States, residing at Newark, in the county of Essex and State 5 of New Jersey, have invented a certain new and useful Improvement in Safety Devices for Power-Presses, of which the following is a full, clear, concise, and exact description.

10 This invention relates to power driven machines such as presses and stamps, and the object is to guard against injury to the operator or workman so that when the treadle or supporting device is inadvertently held in a depressed or abnormal position the machine cannot repeat its operation or stroke and injure the operator.

15 The improvement is useful in a power press where a constantly operating driving part is automatically connected by a spring-actuated clutch with the driven part; and a stop, operated by a treadle, is normally in position to restrain the clutch and hold it open. To start the machine the treadle is 20 depressed to remove the stop, and if the treadle is held down the plunger descends repeatedly. The operator sometimes carelessly or unconsciously holds the treadle down and is hurt when the plunger descends 25 unexpectedly. These machines usually employ a pivoted stop to hold the clutch normally open, with a treadle or device operated by the hand or foot of the workman to move the stop out of engaging position with 30 respect to said clutch. This improvement employs the described clutch and stop and adds a second or duplicate stop which is moved into the position vacated by the first stop when the treadle is depressed, so that 35 if the treadle is held depressed the second stop is in position to open the clutch, and a second descent of the plunger cannot occur until the treadle is allowed to return to its upper limit and is again depressed. A single 40 uni-directional movement of the manually operated means, such as a treadle, removes one stop to start the machine and places another stop in engaging position to release the clutch at the end of one operation of the 45 plunger.

The accompanying drawings illustrate the invention.

Figure 1 is a vertical elevation of a power driven machine partly broken away to 50 show the rotary clutch mechanism; Fig. 2 is

an enlarged section showing the spring-actuated automatic rotary clutch and the two pivoted stops, one of which covers the path of the operating clutch member when the other is out of position; Fig. 3 is an elevation of the same parts as Fig. 2, but is taken at right angles to Fig. 2, and Fig. 4 shows a cross-section of the driving and driven parts, the clutch being held open by reason of engagement of the operating clutch member with one of the stops.

The frame *f* of the machine is of cast iron; the plunger *p* is reciprocated to operate upon work supported upon a bed plate *b*. The plunger *p* is connected to a driven shaft *s*, and shaft *s* is driven by a constantly rotating driving part *r*. The driving part *r* is automatically connected with the driven part *s* by a rotary clutch consisting of a key *k* in a keyway formed in the parts *r* and *s*. 75 The key *k* is of cylindrical form but is reduced in cross section, as shown, over the portion lying within the driving member *r*; and said key rotates in the key way in the shaft *s*. Extending from one end of the key *k* is a finger *o*, of the form shown, which is engaged by an expansion spring *10*, the other end of which is supported by a lug 11 projecting from the face of the brake disk *s'*. The spring *10* tends to move the 80 key *k* into the position in which it serves as a driving connection between the driving member *r* and the shaft *s*. Mounted on the shaft *12* journaled in the bracket *13*, is a stop *x* arranged to coöperate with the finger *o* to move the key *k* to releasing position, in a well known manner. This shaft *12* is turned by a treadle *t*, retracted by a spring *14*. The treadle *t* is connected with the shaft *12* by a rod *15* pivoted to an arm 85 16 fixed on shaft *12*. The spring *14* tends to normally hold pivoted stop *x* in position to engage operating clutch member *o* as it rotates in a counter-clockwise direction, and when so engaged key *k* is in the position 90 shown in full lines in Fig. 3 and the part *r* runs free.

To start the machine, treadle *t* is depressed by foot or hand; the stop *x* is moved out of the path of the member *o*; the spring *10* rotates the key *k* and causes it to unite the driving part *r* with the driven shaft *s*; the shaft *s* makes one complete rotation; and the plunger *p* descends and returns, an operation which would continue repeatedly if the 100 110

treadle were held down and the additional device about to be described were not present. This additional device consists of a second stop y , fixed to the shaft 12, and located in close proximity to the stop x , but set at an angle of from ten to fifteen degrees with reference thereto. With this arrangement, if the treadle t is not released in time to allow the stop x to take its normal position in which it lies in the path of the end of the finger o , the stop y will be in position to engage the end of the finger o and will rotate the key k to its non-holding position, as shown in Fig. 4. If, after the stop y has engaged the finger o in the manner just described, the treadle t is allowed to rise, the stop y moves out of the path of the end of the finger o and the stop x moves into position to engage the finger o and hold it in the position in which the key k is inoperative as a driving connection.

With the arrangement above described, it is obvious that the plunger p of the press can never descend more than once for a single depression of the treadle t . There is, therefore, no danger that the operator will be injured by unexpected repeated reciprocation of the plunger when he depresses the treadle and desires only a single operation of the press.

What I claim is:—

1. In a power driven machine, the combination of a driving part, a driven part, a device for automatically connecting said parts, and means for releasing and then restraining said device at the limits of one movement of said driven part, consisting of a pair of stops for said connecting device, and a manually operated controlling device for removing one stop and moving the other into restraining position by a single movement thereof.

2. In a power driven machine, the combination of an automatic clutch for connect-

ing the driving and driven parts, duplicate devices for releasing and restraining said clutch, a manually operated controlling device, and means whereby a single uni-directional movement substitutes one of said duplicate devices for the other and permits a single operation of said machine.

3. In a power driven machine, the combination of a clutch for connecting the driving and driven parts, a plurality of devices for releasing and restraining said clutch, a treadle for controlling said devices, and means whereby the depression of said treadle removes one device to start said machine and substitutes another device to stop said machine by a single uni-directional movement.

4. In a power driven machine, a driving part, a driven part, and means for operatively connecting said parts together comprising a clutch mechanism having an operating finger, a stop adapted to coöperate with said finger to release the clutch mechanism, means for moving said stop into and out of the path of said finger, and another stop movable with said first named stop into the path of said finger when the first stop moves out of said path.

5. In combination with a rotary clutch having an operating finger projecting therefrom, a stop adapted to coöperate with said finger, means for moving said stop into and out of the path of said finger, and a second stop movable with said first-named stop and arranged to lie in the path of said finger when the first named stop is out of said path.

In witness whereof, I hereunto subscribe my name this 28th day of November, A. D. 1910.

MILTON E. WINANS.
